PROCESS OF PRODUCING AN ANTIKNOCK COMPOUND

Filed June 15, 1927

UNITED STATES PATENT OFFICE

HARRY KARL IHRIG, OF BERKELEY, CALIFORNIA

PROCESS OF PRODUCING AN ANTIKNOCK COMPOUND

Application filed June 15, 1927. Serial No. 199,119.

This invention relates to the preparation of an anti-detonating compound which is a hydrogenated nitrogen hydrocarbon mixture.

It has been found that certain compounds, either naturally present or purposely added to gasoline, will minimize and in some cases entirely eliminate detonation. Undoubtedly the presence of aromatic hydrocarbons to a large extent accomplishes this purpose.

10 However, the presence of these compounds may be insufficient to entirely eliminate knocking in higher compression engines, in which case it is necessary to add an additional proportion of such compounds to prevent detonation.

Certain crude petroleums contain large quantities of aromatic hydrocarbons, and it is with these that this process deals primarily. These aromatic hydrocarbons are objectionable in kerosene and are eliminated along with other impurities by reason of their solubility in a polar solvent, such as liquid sulphur dioxide. These impurities, together with the polar solvent, are concentrated in an extract which may be separated from the insoluble hydrocarbons, which are termed raffinat, or refined petroleum products. It has been found that this extract, which has heretofore had a value about the same as fuel oil, may now be used as the starting point for the production of this compound, which, when mixed with gasoline, will produce an anti-knock motor fuel.

25 The principal object of this invention is, therefore, to produce a cheap non-poisonous and non-metallic anti-knock compound or mixture, which, when added to a low compression engine fuel, will produce a fuel that will meet the desired requirements.

30 This invention relates generally to the treatment of hydrocarbon materials with a polar solvent to obtain an extract consisting of aromatic, hydroaromatic and unsaturated hydrocarbons, concentrated in a relatively small volume; treating said extract with a suitable reagent such as 93% sulphuric acid for the removal of the unsaturated hydrocarbons, thereby leaving a remainder, comprising a mixture of aromatic, hydroaromatic and partially hydrogenated aromatic com-

pounds; nitrating said remainder or any distillate fraction thereof; reducing said nitrated remainder; and subjecting it to steam distillation and extraction with a suitable solvent to obtain a hydrogenated nitrogen hydrocarbon mixture.

The accompanying flow sheet diagrammatically illustrates my process.

45 My invention more in detail now will be fully disclosed:

First, as to the preparation of the extract:

A number of crude oils are known to contain hydrocarbons other than the saturated straight chain hydrocarbons. These hydrocarbons may be classified as unsaturated, hydroaromatic, and aromatic hydrocarbons. Sometimes, hydroaromatic hydrocarbons are known as naphthenes, or hydrocarbons of the general type C_nH_{2n} , while the aromatic hydrocarbons have the general formula C_nH_{2n-6} .

50 In refining of oils other than those containing the first type or saturated straight chain hydrocarbons, there is difficulty using the ordinary methods of refining. In general, these latter types of hydrocarbons, or unsaturated, hydro-aromatic and aromatic hydrocarbons, can be called "polar compounds", as differentiated from the saturated or non-polar hydrocarbons. The fully hydrogenated aromatic compounds are midway between the non-polar and polar types.

55 In order to separate polar hydrocarbons from non-polar hydrocarbons, it is necessary to employ some means other than distillation. One of these means is the extraction with a polar solvent; the polar hydrocarbons going into solution in the polar solvent, and the non-polar hydrocarbons remaining behind as a separate layer. Such polar solvents are liquid sulphur dioxide, liquid ammonia, or liquid hydrochloric acid. These compounds are solvents at ordinary temperatures and pressures, and hence can be readily removed after the extraction has been made, and then can be used for further treatment by reason of the continuous cycle.

60 The polar solvent most used in petroleum refining is liquid sulphur dioxide, because of its cheapness and relative ease of liquefac-

tion. In using liquid sulphur dioxide, the hydrocarbon material is agitated with liquid sulphur dioxide at 0° F. and 1 pound gauge pressure. This may be done either in batches or continuously, by having the liquid sulphur dioxide flow countercurrently with the hydrocarbon material. After the liquid sulphur dioxide has become thoroughly mixed in intimate contact with the hydrocarbon material, the mixture is allowed to settle. Two layers are observed; a top layer, which consists of the non-polar type of hydrocarbon, relatively free of sulphur dioxide; and a lower layer, composed of a solution of the polar hydrocarbons, other impurities and the liquid sulphur dioxide. The lower layer, which is the extract, is drawn off and the sulphur dioxide evaporated for further use in the cycle. The upper layer is called raffinat, and consists of the non-polar hydrocarbons and is used either as such or given appropriate, additional refining treatment to make the high quality refined oil products. The extract, which is the starting point of this process, consists of unsaturated, hydroaromatic and aromatic hydrocarbons, concentrated in a relatively small volume. This material is therefore a valuable source for the production of derivatives of the above mentioned hydrocarbons concentrated in it. In preparing the extract, the hydrocarbon material is chosen of appropriate boiling range to make the desired derivative. In the refining of kerosene, the starting material is called "kerosene extract", while in the refining of cracked gasoline or pressure distillate, the material is known as "pressure distillate extract".

Any hydrocarbon material may be treated with the polar solvent mentioned above and the extract utilized to give the corresponding derivatives when treated according to description submitted herein.

For an example of actual operation, which is not to be construed in any way as a limitation, the following run was made:

About 500 gallons of pressure distillate from the cracking of California petroleum was treated with liquid sulphur dioxide, 50% by volume, 0° F., by exhaustive extraction, from which was obtained 62.36% of raffinat, or non-polar hydrocarbon, and 35.71% was recovered as extract of polar hydrocarbon. This extract has a gravity of 31.4° A. P. I. and 60° F., initial boiling point of 176° F. and an end point of 546° F. 175 gallons of this extract was then washed with water to free it from the sulphur dioxide and was then treated with 43 gallons of 93% sulphuric acid in six batches, drawing off the sludge each time which contains the bulk of the unsaturated hydrocarbons soluble therein, such as olefines, some of the olefines being polymerized and remain in the insoluble portion of the mixture. The hydrocarbon mixture

was neutralized and washed and then distilled with fire and steam to remove the polymerized compound containing hydroaromatic, aromatic and polymerized olefinic hydrocarbons. The distillate after separation from the steam condensate was fractionated in a 15 gallon still with a 10 foot tower, from which a cut was made between the range of 370° to 380° F. This fraction was nitrated with an equal volume of concentrated nitric acid and one of concentrated sulphuric acid, and a liquid nitro compound or mixture of compounds was obtained. No attempt was made to purify this product but it was simply washed with water and then reduced. The reduction was accomplished by treating 200 grams with 400 grams of iron filings, 40 Cs. of concentrated hydrochloric acid and 30 Cs. of water, the acid being added slowly, while the heat of reaction was reduced by cooling with water. After the acid had been added, the mixture was heated on the water bath for an hour, then made alkaline and steam distilled. That part of the distillate which was soluble in the steam condensate was extracted with any suitable solvent such as ether, dried with solid caustic soda, and was then ready for blending with gasoline, kerosene or the like, after the solvent had been distilled off. Of course, if gasoline was used as the solvent it would not be necessary to remove the solvent. This mixture of hydrogenated nitrogen hydrocarbons was a brown liquid, soluble in hydrochloric acid and gave a marked reaction with acetyl chloride.

The product obtained from this particular run was mixed in small portions with low compression fuel such as kerosene or gasoline and it was found to produce an excellent anti-detonating motor fuel.

Fractions may be taken over a range from 100° to 550° F. according to the facility with which they may be nitrated, and various aromatic hydrocarbons which are amino derivatives are produced. While this process is designed to so treat the extract as to produce a mixture of hydrogenated nitrogen hydrocarbons, among which the aromatic amines have been identified, it should be apparent that these amines may be separated if desired. This mixture need not be further treated or purified as it efficiently accomplishes the purpose for which it is produced.

What I claim is:

1. The method of producing aromatic hydrocarbon derivatives, which comprises treating a hydrocarbon material with a polar solvent to form an extract soluble therein, in which are concentrated the aromatic, hydroaromatic and unsaturated compounds; separating from said extract the unsaturated compounds; and treating a remainder of said

extract to produce a mixture of aromatic amines.

2. The method of producing a hydrocarbon mixture, containing aromatic amines, which comprises treating a hydrocarbon material with a polar solvent to form an extract soluble therein, in which are concentrated the aromatic, hydroaromatic and unsaturated compounds; separating from said extract the unsaturated compounds; nitrating a remainder of said extract; and treating the nitro compound mixture to produce the desired mixture of aromatic amines.

3. The method of producing a hydrocarbon mixture, containing aromatic amines, which comprises treating a hydrocarbon material with a polar solvent to form an extract soluble therein, in which are concentrated the aromatic, hydroaromatic and unsaturated compounds, separating from said extract the unsaturated compounds; nitrating a remainder of said extract; reducing the nitro compound mixture; and treating to obtain the desired mixture of aromatic amines.

4. The method of producing a hydrocarbon mixture, containing aromatic amines, which comprises treating a hydrocarbon material with a polar solvent to form an extract soluble therein, in which are concentrated the aromatic, hydroaromatic and unsaturated compounds; separating from said extract the unsaturated compounds; nitrating a remainder of said extract; reducing the nitro compound mixture; purifying by distillation; and treating to obtain the desired mixture of aromatic amines.

5. The method of producing a hydrocarbon mixture, containing aromatic amines, which comprises treating a hydrocarbon material with a polar solvent to form an extract soluble therein, in which are concentrated the aromatic, hydroaromatic and unsaturated compounds; separating from said extract the unsaturated compounds; nitrating a remainder of said extract; reducing the nitro compound mixture; purifying by steam distillation; and extracting an additional portion of the desired mixture of aromatic amines with a suitable solvent from the steam condensate.

6. A process of producing aromatic amines, which comprises treating a hydrocarbon material with a polar solvent to form an extract soluble therein, in which are concentrated the aromatic, hydroaromatic and unsaturated compounds; separating from said extract the unsaturated compounds; nitrating a remainder of said extract; reducing the nitro compound mixture; and treating to separate the particular aromatic amine desired.

7. A method of producing a mixture containing aromatic amines, which comprises treating a hydrocarbon material with a polar solvent to form an extract soluble therein, in which are concentrated the aromatic, hydroaromatic and unsaturated compounds; sepa-

rating from said extract the unsaturated compounds; oxidizing and nitrating the remainder of said extract; reducing the nitro compound mixture; purifying by steam distillation; and extracting an additional portion of the desired mixture of aromatic amines with a suitable solvent from the steam condensate.

8. A process of treating a mixture of hydrocarbons containing olefines, hydroaromatics and aromatics which comprises: adding sulphuric acid to said mixture to dissolve out certain unsaturated compounds, removing the acid and dissolved compounds, fractionating the remaining compounds, nitrating a selected fraction, reducing the nitrated fraction, and treating the reduced fraction to separate a portion containing aromatic amino derivatives.

9. A process of treating a mixture of hydrocarbons containing olefines, hydroaromatics and aromatics which comprises: adding 85 93% sulphuric acid to said mixture to dissolve out certain unsaturated compounds, removing the acid and dissolved compounds, fractionating the remaining compounds, nitrating a selected fraction, reducing the nitrated fraction, and treating the reduced fraction to separate a portion containing aromatic amino derivatives.

10. A process of treating a mixture of hydrocarbons containing olefines, hydroaromatics and aromatics which comprises: adding sulphuric acid to said mixture to dissolve out certain unsaturated compounds, removing the acid and dissolved compounds, fractionating the remaining compounds, nitrating a selected fraction having a boiling range from 100° F. to 550° F., reducing the nitrated fraction, and treating the reduced fraction to separate a portion containing aromatic 105 amino derivatives.

11. A process of treating a mixture of hydrocarbons containing olefines, hydroaromatics and aromatics which comprises: adding sulphuric acid to said mixture to dissolve out certain unsaturated compounds, removing the acid and dissolved compounds, fractionating the remaining compounds, nitrating a selected fraction having a boiling range from 370° F. to 380° F., reducing the nitrated fraction, and treating the reduced fraction to separate a portion containing aromatic amino derivatives.

12. A process of treating a mixture of hydrocarbons containing olefines, hydroaromatics and aromatics which comprises: adding sulphuric acid to said mixture to dissolve out certain unsaturated compounds, removing the acid and dissolved compounds, fractionating the remaining compounds, nitrating a selected fraction, reducing the nitrated fraction, distilling the reduced fraction with steam, and extracting that part of said fraction soluble in the steam condensate with a suitable solvent.

13. A process of treating a mixture of hydrocarbons containing olefines, hydroaromatics and aromatics which comprises: adding sulphuric acid to said mixture to dissolve out certain unsaturated compounds, removing the acid and dissolved compounds, frictionating the remaining compounds, nitrating a selected fraction, reducing the nitrated fraction, distilling the reduced fraction with steam, and extracting that part of said fraction soluble in the steam condensate with gasoline.
